(57) **CLAIM**

The ornamental design for motorcycle tires, as shown and described.

DESCRIPTION

FIG. 1 is a perspective view of a motorcycle tire, showing our new design;

FIG. 2 is a top view thereof;

FIG. 3 is a bottom view thereof;

FIG. 4 is a front view thereof;

FIG. 5 is a rear view thereof;

FIG. 6 is a right side elevation view thereof;

FIG. 7 is a left side elevation view thereof; and,

FIG. 8 is an enlarged front perspective view of FIG. 2, showing a portion thereof.

The broken dash-dot lines of even length illustrate portions of the tire that form no part of the claimed design. The broken dot-dash lines of uneven length define the boundary of the claimed design. The broken dot-dot lines in FIGS. 2 and 8 illustrate the boundary of the enlarged portions of the top views.
